DESIGN FOR A DISPLAY PANEL

Clifton O. Lash, Kansas City, Mo.

Application August 3, 1940, Serial No. 94,197

Term of patent 7 years

To all whom it may concern:

Be it known that I, Clifton O. Lash, a citizen of the United States, residing at Kansas City, in the county of Jackson and State of Missouri, have invented a new, original, and ornamental Design for a Display Panel, of which the following is a specification, reference being had to the accompanying drawing, forming a part thereof.

Fig. 1 of the drawing is a face view of a display panel showing my new design, and

Fig. 2 is a fragmentary sectional view taken on the line 2—2 of Fig. 1.

It is contemplated that other contrasting colors than those indicated on the drawing may be employed.

I claim:

The ornamental design for a display panel, substantially as shown and described.

CLIFTON O. LASH.
